METHOD OF DISTILLING HEAVY
PETROLEUM OILS

George B. Coubrough, Long Beach, Calif., assignor
to The Lummus Company, New York, N. Y., a
corporation of Delaware

Application October 5, 1932, Serial No. 636,347

15 Claims. (Cl. 196—77)

The present invention relates to methods of distilling heavy petroleum oils, particularly heavy oils which are associated with only small quantities of unvaporizable residuum.

5 It is well-known that the most valuable lubricating oils are those of highest viscosity and high boiling point which are also the oils most susceptible to injury when it is attempted to distill them from intimate solution with non-volatile 60 components, such as asphaltum. In particular, high viscosity oils of Pennsylvania and other crudes having only a small content of asphalt, cannot ordinarily be obtained by distillation, but must be stripped of lighter oils and collected 65 10 as a residuum requiring expensive acid treatment methods to purify the oils to suitable commercial standards.

The present invention provides a method for the continuous distillation and concentration of 20 heavy lubricating oils from crudes having only a small content of unvaporizable residuum.

I have discovered that heavy petroleum oils that are highly susceptible to decomposition or cracking by overheating may be distilled without 25 injury at minimum temperatures if heated and flashed from mixtures which have been altered to contain certain favorable proportions of lighter oils and also of unvaporizable residuum. My improved method takes advantage of this discovery and consists essentially of altering the 30 composition of the material to be distilled so as to form a mixture of favorable proportions for distilling at a temperature below that at which decomposition or cracking can occur.

35 The process is carried out in apparatus of the general type used for continuous distillation. The materials are first heated under conditions in which no opportunity for gradual or progressive vaporization is present, as in a pipe still, 40 and are then released into a vaporizing zone maintained under vacuum wherein the oils undergo a collective or flash vaporization due to the pressure drop between the heater and the vaporizing zone.

45 In order that sufficient heat may be imparted to the starting mixture to effect flash vaporization of all of the oils, but without the necessity of heating to an unsafe temperature at any point, I alter the composition of the original material by adding thereto materials having both non-volatile components and other components 50 more volatile than the oils to be distilled.

It will be understood that flash vaporization of the oils occurs entirely under the heat previously imparted in the heater, the latent heat

of the oils being furnished by a part of their own sensible heat as well as by a part of the sensible heat of the unvaporized residue. Inasmuch as the latent heat of the oils is accompanied by a reduction of the sensible heat of the entire mixture, a temperature differential necessarily exists between the heater and the flashing zone. According to the present invention, the non-volatile material added to the original mixture affords a large store of sensible heat at a low 65 temperature so that the conversion into latent heat may be accomplished without an excessive differential of temperature between the heater and the flash zone. For practical reasons, the added non-volatile material is preferably asphalt. This asphalt, in mixture with any unvaporizable material originally present, is continuously recovered as residue, and all or part thereof may be continuously recirculated to be 70 mixed with the bottoms entering the heater.

The more volatile or lighter materials added to the original mixture preferably comprise a kerosene or light gas oil fraction with a narrow range of boiling points materially lower than the boiling point of the heavy oil to be distilled. 80 The purpose of this material is to form a mixture with the heavy oils such that when flashed under vacuum, the collective flash temperature will be materially lower than that of the heavy oils 85 themselves.

The heavy oils to be distilled are therefore subjected to the influence of two factors, one of which controls the temperature at which flash vaporization can occur at the pressure employed, and the other of which controls the supply of 90 heat required for vaporization without greatly exceeding that temperature.

I have found that a temperature of about 720° F. is the maximum that need be reached in the heater to vaporize all of the heaviest oils under a moderate vacuum to produce asphaltic residues substantially free of oils and a distillate vapor mixture containing substantially all the heavy oils of the original material.

With a view to the sharpest possible separation 100 of the high viscosity lubricating or heavy oils from the lighter diluent oils contained in the distillate vapor mixture, I prefer that the starting material, which can be selected for its favorable content of heavy lubricating oils, shall have 105 been subjected to a preliminary distillation to eliminate oils of closely related composition and of only moderately lower boiling point such, for example, as wax distillate. Then the altered mixture which is subjected to the final distillation 110

will consist of a mixture of (1) heavy lubricating oils such as cylinder stock, (2) added lighter oils such as kerosene, which will flash with the heavy oils at a mean collective boiling point but are yet 5 of sufficiently unrelated character and low boiling point to be readily separable from the heavy oils by rectification, and (3) asphaltum or asphaltic residuum.

The accompanying drawing is a diagram of the 10 preferred form of apparatus for practising the present invention.

The invention is herein illustrated and described as embodied in the process of obtaining cylinder stock as distillate. The crude is first 15 subjected to preliminary distillation steps to eliminate therefrom oils more volatile than the cylinder stock and the final residue of such steps, consisting of cylinder stock in mixture with a small amount of asphalt is then mixed with the more volatile and non-volatile materials to be subjected to the final flash vaporization.

In the apparatus shown in the drawing, the crude oil which has been preferably subjected to a preliminary treatment to remove a part of the 25 gasoline, as well as impurities, is introduced through a pipe 2 and a heater 4 to a column 6, wherein gasoline is obtained as an overhead vapor product at 8 and kerosene and gas oil are obtained as side products from the draw-off pipes 30 10 and 12 respectively. The residue of the column 6 is withdrawn by the pipe 14 and is introduced through a heater 16 into a second column 18 to obtain gas oil as an overhead product through the pipe 20 and pressable wax distillate 35 as a side product at the draw-off 22. Preferably, this column operates at atmospheric pressure under steam distillation by steam introduced at the bottom through a pipe 24. A slop cut consisting of a mixture of wax distillate and cylinder 40 stock may be taken off as a side product at 25. By this preliminary distillation, the bottoms are reduced to a mixture of asphalt with cylinder stock of substantially any desired specifications.

The residue from the column 18 is withdrawn 45 by the pipe 26. This residue comprises the starting material for the main process, namely, a mixture containing only cylinder stock and asphalt. To this starting material is continuously added a mixture of materials, consisting of both light 50 gas oil and asphalt. The gas oil is conducted from the draw-off 12 of column 6 through a pipe 28 by a pump 29, the pipe 28 connecting with the pipe 26. Asphalt is introduced into the pipe 26 through a pipe 30, which may lead either from a 55 storage receptacle or from the final column, as will presently be explained. The entire mixture, comprising the residue from column 18, the gas oil and the asphalt, is continuously pumped through a heater 31 to be elevated to a high tem- 60 perature (but below the cracking point), and is then released into a final column 32 having a flashing zone 33. This last column is maintained under vacuum. Steam may be introduced at 34, in which case only a moderate vacuum need be 65 employed. The use of a moderate vacuum in conjunction with steam is preferred, since a very high vacuum may promote entrainment or distillation of asphalt with a corresponding contamination of the distillates.

70 The asphaltic residue is withdrawn from the bottom of the column at 35. If desired, a portion thereof may be taken off as a product, and the remainder returned through a pipe 36 and pump 37 to the line 30.

75 The mixed vapors of gas oil and cylinder stock

which have vaporized as a unit from the asphalt pass upwardly through entrainment catchers 38 and thence through a vapor pipe 40 which rises from a deck 42. The deck 42 is imperforate, except for the vapor passage, it being essential to prevent passage of reflux condensate into contact with the initial vapors which would result in a diminution in the temperature of the flashing zone, and would therefore require a compensating increase in the temperature of heating.

The overhead vapors are conducted by a pipe 44 to a condenser 46 which is connected with any suitable vacuum pump or jet. When steam is used, the condensate is collected in a decanter 48, the water is drawn off at 50, and a part of the oil condensate is returned through the pipe 52 to a reflux section 53 in the upper part of the column, the remainder being drawn off through the valved pipe 54 as a product. This condensate is of the same composition as the gas oil introduced through the pipe 28. The gas oil reflux condenses the cylinder stock vapor which is collected as a liquid on the deck 42 and is withdrawn at 56. The annular space around the vapor pipe 40 is preferably provided with decks 58 forming a restripping section into which steam is introduced at 60 for distilling off any remnant of gas oil which may pass downwardly toward the deck 42. The upper section of the column requires only a few decks, since a practically complete separation between the cylinder stock and the diluent oil can be effected by a minimum of reflux.

The character and amount of the added materials are not critical. The light or diluent oil should be of sufficiently related properties to the 110 heavy oils so that it may be collectively flashed with them, and is preferably a fraction of the same series obtained from the crude oil; on the other hand, it should have unrelated or non-adjacent properties with respect to boiling point 115 and vapor pressure and is preferably of a character to vaporize completely under conditions of pressure and temperature at which vaporization of the cylinder stock would be negligible. That is to say, the light oil should be of materially 120 lower boiling point than the cylinder stock to insure collective vaporization at a low temperature and also to facilitate separation in the portion 53 of the column. Moreover, it should be stable at any temperature encountered in the 125 process and should be readily condensable at temperatures obtainable with ordinary cooling water. A gas oil or kerosene cut is satisfactory, particularly if it has narrow limits of initial and end 130 points, such as 450°-550° F., at atmospheric pressure.

The added non-volatile material, as previously stated, is preferably though not necessarily asphalt.

In general, the amount of added volatile oil 135 should be sufficient to lower the collective flash point of all the oils to a point well below the cracking temperature, and the quantity of added heat storage material, together with such asphalt as is present in the starting material, should be sufficient to provide the heat of vaporization of the vapors without an excessive differential of temperature between the pipe still and the vaporizing chamber. With average bottoms, the best quantity of volatile oil will be about equal to the 140 quantity of heavy oils in the mixture, and the total quantity of asphalt, including that contained in the starting material, will be about equal to the quantity of heavy oils. Under such conditions, when an absolute pressure of 50 to 100 mm. 145 150

is maintained in the flashing zone, distillation can be effected with a maximum pipe still temperature not in excess of 700° F.

As a specific example of my process, I may take 5 a Pennsylvania crude which contains approximately 20% of lubricating stock and about 1% of unvaporizable asphaltic residuum. The crude is reduced to 10% bottoms by distillation of 90% by volume of lighter materials in the preliminary 10 columns. This 10% figure is illustrative only, and the crude may be reduced to bottoms of any 15 specifications, ranging from 10 to approximately 20%, depending on the character of the final product desired. The 10% bottoms, constituting the starting material for the final process, therefore 20 comprise 9 parts of lubricating stock and 1 part of asphalt by volume. With this starting material are mixed 8 parts of asphalt (for example, asphalt of 100 penetration previously obtained 25 from a Smackover crude) and 9 parts by volume of gas oil or kerosene. The starting material composition thus altered to provide substantially 30 equal parts of asphalt, lubricating stock and diluent, is then heated to about 700° in the pipe 35 still 31 and introduced into the column 32 which is maintained under an absolute pressure of about 75 mm. The actual pressure and temperature 40 are interdependent, and the temperature may be reduced by increasing the vacuum, and vice versa. In any event, the vacuum is such that complete 45 vaporization of the oils occurs without exceeding the cracking point.

The operation results in recovery of the diluent as the overhead product, all of the lubricating stock as a side product, and a residue 50 consisting of the asphalt of the original crude, together with that mixed therewith. After the process is started, the mixing of asphalt with the starting material may be carried out as above 55 described, or a portion of the asphalt may be recirculated, as illustrated in the drawing. It will be evident that the proportion of recirculated asphalt will be such as to maintain the desired proportions in the starting mixture.

55 In the specific example given above, it will be noted that the oils are recovered as a pure Pennsylvania overhead stock. If blended lubricating oils are desired, the blending may be carried out prior to the final vaporizing operations. For 60 example, a blend of 10% Pennsylvania bottoms may be made with, say, 25% bottoms of Smackover crude, which has a high asphalt content, the proportion of the blended bottoms being such as to give approximately equal parts of asphalt and 65 lubricating stock. To this blended mixture, the diluent, such as kerosene or gas oil, is added, and the distillation is carried out as above described.

The present invention is of greatest value in 70 refining crude oils having only a small asphalt content. When the crude has more than a certain minimum, generally about 6% of asphalt, it can be reduced in the preliminary columns to obtain bottoms having about equal proportions 75 of asphalt and heavy oils. Such bottoms form a favorable mixture for flash vaporization upon the addition of a diluent thereto, in accordance with the principles described in my Patent No. 1,905,156.

When the original crude contains less than the 75 minimum of about 6% asphalt, the crude cannot usually be reduced in the preliminary columns to bottoms having the desired quantity of asphalt unless at some point a cracking temperature is reached. According to the present invention, as typified in the above example, it is not necessary

to reduce any crude to less than about 10% in the preliminary stages, final operations being carried out by adding both asphalt and diluent, followed by flashing in the final column.

Having thus described the invention, what is 80 claimed is:

1. The method of recovering oils and residuum from petroleum bottoms containing primarily lubricating oils with a small amount of non-volatile residuum which consists in adding to the bottoms a diluent which can be completely vaporized under conditions at which vaporization of the bottoms would be negligible, adding to the mixture a quantity of non-volatile heat storage medium, subjecting the oils to flash vaporization by continuously heating the mixture in a confined stream and releasing the heated mixture into a vaporizing zone maintained under vacuum to vaporize all of the oils as a unit from the residuum under the contained heat of the mixture, condensing the vapors, and withdrawing non-volatile residue. 85

2. The method of recovering oils and asphalt from petroleum bottoms containing primarily lubricating oils with a small amount of non-volatile asphaltic residuum which consists in adding to the bottoms a diluent which can be completely vaporized under conditions at which vaporization of the bottoms would be negligible, adding to the mixture a quantity of asphalt as a heat 100 storage medium, subjecting the oils to flash vaporization by continuously heating the mixture in a confined stream and releasing the heated mixture into a vaporizing zone maintained under vacuum to vaporize all of the oils as a unit from the asphalt under 105 the contained heat of the mixture, condensing the vapors, and withdrawing asphalt as residue. 110

3. The method of recovering oils and asphalt from petroleum bottoms containing primarily lubricating oils with a small amount of non-volatile asphaltic residuum which consists in adding to the bottoms a diluent which can be completely vaporized under conditions at which vaporization of the bottoms would be negligible, 115 subjecting oils to flash vaporization by continuously heating the mixture in a confined stream and releasing the heated mixture into a vaporizing zone maintained under vacuum to vaporize all of the oils as a unit from the asphalt under 120 the contained heat of the mixture, condensing the vapors, withdrawing asphalt as residue, and recirculating a portion of the withdrawn asphalt to be mixed and heated with the original mixture to increase the heat content of the 125 material supplied to the vaporizing zone. 130

4. The method of separately recovering cylinder stock as an overhead product and asphalt as residue from a mixture thereof having only a small content of asphalt which consists 135 in adding to the mixture a material at least as volatile as gas oil, continuously heating the mixture, releasing the heated mixture into a vaporizing zone at a pressure low enough to vaporize the oils by the contained heat of the mixture, 140 condensing the vapors, and recirculating a part of the asphalt residue to be added to the original mixture to act as a heat storage medium in the vaporizing zone. 145

5. The method of separately recovering cylinder stock as an overhead product and asphalt as residue from a mixture thereof substantially free of wax distillate having only a small asphalt content which consists in adding to the mixture a material at least as volatile as gas oil, adding 150

asphalt as a heat storage medium, continuously heating the mixture, releasing the heated mixture into a vaporizing zone at a pressure low enough to vaporize the oils by the contained heat of the mixture, condensing the vapors, and withdrawing asphalt as residue.

6. The method of separately recovering cylinder stock as an overhead product and asphalt as residue from a mixture thereof substantially free of wax distillate and having only a small quantity of asphalt which consists in adding to the mixture a low-boiling petroleum fraction, at least as volatile as gas oil, continuously heating the mixture, releasing the heated mixture into a vaporizing zone at a pressure low enough to vaporize the combined oils by the contained heat of the mixture, withdrawing the vapors, and recirculating a part of the asphalt residue to be added to the mixture to act as a heat storage medium in the vaporizing zone.

7. The method of dividing petroleum oils which consists in fractionally distilling from the oil several fractions of increasing boiling points including wax distillate, leaving a residual mixture consisting of a mixture of cylinder stock and a small quantity of asphalt, adding to the residual mixture a petroleum fraction at least as volatile as gas oil, adding asphalt as a heat storage medium, continuously heating the mixture, releasing the heated mixture into a vaporizing zone at a pressure low enough to vaporize the combined oils by the contained heat of the mixture, withdrawing the vapors, and leaving asphalt as residue.

8. The method of dividing petroleum oils which consists in fractionally distilling from the oil several fractions of increasing boiling points including wax distillate, leaving a residual mixture consisting of cylinder stock and a small quantity of asphalt, adding to the residual mixture a diluent at least as volatile as gas oil, continuously heating the mixture, releasing the heated mixture into a vaporizing zone at a pressure low enough to vaporize the combined oils by the contained heat of the mixture, withdrawing the vapors and leaving asphalt as residue, recirculating a portion of the asphalt to the mixture to be heated, and separately condensing the cylinder stock and the diluent.

9. The method of recovering oils and residuum from petroleum bottoms containing primarily lubricating oils with a small amount of non-volatile residuum which consists in adding to the bottoms a diluent which can be completely vaporized under conditions at which vaporization of the bottoms would be negligible, adding a quantity of asphalt as a heat storage medium, the total quantities of diluent, lubricating oils and asphalt in the mixture being in approximately equal proportions, subjecting the oils to flash vaporization by continuously heating the mixture in a confined stream and releasing the heated mixture into a vaporizing zone maintained under vacuum to vaporize all of the oils as a unit from the residuum under the contained heat of the mixture, condensing the vapors, and withdrawing non-volatile residue.

10. The method of recovering oils and asphalt from petroleum bottoms containing primarily lubricating oils with a small amount of non-volatile asphaltic residuum which consists in adding to the bottoms a diluent which can be completely vaporized under conditions at which vaporization of the bottoms would be negligible, adding to the mixture a quantity of asphalt as a heat storage medium, subjecting the oils to flash va-

porization by continuously heating the mixture in a confined stream and releasing the heated mixture into a vaporizing zone maintained under vacuum to vaporize all of the oils as a unit from the asphalt under the contained heat of the mixture, introducing steam into the residue from the vaporizing zone, condensing the vapors, and withdrawing asphalt as residue.

11. The method of recovering oils and asphalt from petroleum bottoms containing primarily lubricating oils with a small amount of non-volatile asphaltic residuum which consists in adding to the bottoms a diluent which can be completely vaporized under conditions at which vaporization of the bottoms would be negligible, subjecting oils to flash vaporization by continuously heating the mixture in a confined stream and releasing the heated mixture into a vaporizing zone maintained under vacuum to vaporize all of the oils as a unit from the asphalt under the contained heat of the mixture, introducing steam into the residue from the vaporizing zone, condensing the vapors, withdrawing asphalt as residue, and recirculating a portion of the withdrawn asphalt to be mixed and heated with the original mixture to increase the heat content of the material supplied to the vaporizing zone.

12. The method of separately recovering cylinder stock as an overhead product and asphalt as residue from a mixture thereof having only a small content of asphalt which consists in adding to the mixture a material at least as volatile as gas oil, continuously heating the mixture, releasing the heated mixture into a vaporizing zone at a pressure low enough to vaporize the oils by the contained heat of the mixture, introducing steam into the residue from the vaporizing zone, condensing the vapors, and recirculating a part of the asphalt residue to be added to the original mixture to act as a heat storage medium in the vaporizing zone.

13. The method of separately recovering cylinder stock as an overhead product and asphalt as residue from a mixture thereof substantially free of wax distillate and having only a small quantity of asphalt which consists in adding to the mixture a low-boiling petroleum fraction, at least as volatile as gas oil, continuously heating the mixture, releasing the heated mixture into a vaporizing zone at a pressure low enough to vaporize the combined oils by the contained heat of the mixture, introducing steam into the residue from the vaporizing zone, condensing the vapors, and recirculating a part of the asphalt residue to be added to the mixture to act as a heat storage medium in the vaporizing zone.

14. The method of dividing petroleum oils which consists in fractionally distilling from the oil several fractions of increasing boiling points including wax distillate, leaving a residual mixture consisting of cylinder stock and a small quantity of asphalt, adding to the residual mixture a diluent at least as volatile as gas oil, continuously heating the mixture, releasing the heated mixture into a vaporizing zone at a pressure low enough to vaporize the combined oils by the contained heat of the mixture, introducing steam into the residue from the vaporizing zone, withdrawing the vapors and leaving asphalt as residue, recirculating a portion of the asphalt to the mixture to be heated, and separately condensing the cylinder stock and the diluent.

15. The method of recovering oils and residuum from petroleum bottoms containing primarily lubricating oils with a small amount of non-
